GARMENT

Henry V. Nier, Los Angeles, Calif.

Application January 3, 1933, Serial No. 649,749

1 Claim. (Cl. 2—79)

This invention is a garment adapted to protect the wearer against cold and drafts, as for example in the case of illness, or during or after exercising, or when the body is being massaged.

5 It is an object of the invention to provide a garment which when in use completely covers the wearer, and which has openings so arranged as to permit the garment being readily put on or taken off, with the openings adapted to be readily closed 10 so that the garment completely encloses the wearer.

It is a further object of the invention to arrange the openings in the garment so that it may be put on and taken off with minimum movement or effort on the part of the user, thereby providing a garment which is particularly applicable to bed-ridden patients, and to arrange the openings so that any desired portion of the body may be exposed while the garment completely covers the 20 remainder of the body, thus particularly adapting the garment for use on surgical patients or when massaging or bathing the body, in order that a wound or incision may be dressed or any desired portion of the body may be massaged or bathed, 25 with only the desired portion of the body exposed.

More particularly it is an object of the invention to provide a garment having a longitudinal opening medially of that portion of the garment which is adapted to cover the trunk of the body, 30 with additional openings extending along portions of the garment which are adapted to receive projecting parts of the body such as the legs, so that by unfastening both the longitudinal medial opening and said additional openings, the entire 35 garment may be readily put on or taken off.

It is a still further object of the invention to provide the openings with fastening means which may be readily manipulated to quickly and completely close the openings along their entire length 40 so that the garment completely encloses the wearer, or which may be as readily manipulated for unfastening any desired portion of any of the openings, so as to expose only a desired portion of the body while the wearer remains otherwise 45 completely enclosed and protected by the garment.

Further objects of the invention will be readily understood from the following description of the accompanying drawing, in which:

50 Fig. 1 is a front perspective view showing the garment completely covering and enclosing the wearer.

Fig. 2 is a similar view showing the garment unfastened.

55 The garment may be made of any suitable ma-

terial whereby it affords desired protection against cold and drafts, the choice of material being determined by its use by different wearers, such as surgical or medical patients, bed-ridden or convalescent, or persons wearing the garment while being massaged or while taking sun baths or the like, or sportsmen wearing the garment either while exercising or playing various games, or as a protector to be put on while cooling off after such exercising.

The garment is adapted to enclose the trunk of the body and the legs and arms, and may have a hood for the head integral with the garment. The garment has a longitudinal opening at the front of that portion of the garment which covers the 15 trunk of the body, with additional openings extending along the legs of the garment, and with the hood for the head having an opening from its top to bottom; and the various openings have fastening means adapted to quickly and completely close the openings, or permitting of partial unfastening of any desired opening, and shown as fastening means of the well known type herein-after referred to as running fasteners, and comprising cooperating rows of projections along each 20 side of an opening, with an actuating element adapted to be slid in opposite directions along the cooperating rows of projections for respectively engaging the cooperating projections and closing the opening, or disengaging said cooperating 25 projections for unfastening any desired length of the opening.

The garment includes a portion adapted to enclose the trunk of the body and comprising a back 35 1 and a front 2, and having sleeves 3 projecting laterally therefrom and preferably terminating in gloves 4, and also having depending legs 5 branching from the crotch 6 and preferably terminating in socks 7. A hood which is adapted to enclose the head projects upwardly from the neck portion of the garment as an integral part thereof, and the front of the hood may be cut away to expose a portion of the face as shown at 26.

An opening 11^a extends down the front of the 45 trunk portion of the garment to the crotch 6, and the back and face of the hood respectively project upwardly integrally with the back and front portions of neck 8^a as shown at 14^a and 15^a, with the face and back of the hood forming an integral 50 structure at one side edge, and at their opposite side edges defining an opening 11^b which is a continuation of opening 11^a and which extends to the top of the hood. At the crotch 6 the opening 11^a branches to form continuations of the opening 55

extending down the respective legs as shown at 11^c. Running fasteners are provided for the openings, with the slide 21 of one fastener adapted to be drawn downwardly to the crotch 6 from the 5 top of the hood for closing the continuous opening 11^a—11^b, and a slide 21 adapted to be drawn upwardly to the crotch 6 and along each of the openings 11^c for respectively closing these openings. It will thus be seen that the garment may be 10 readily put on by unfastening the various openings as shown in Fig. 2, with the garment completely enclosing the body when the openings have 15 been closed as shown in Fig. 1, and a portion of the body adapted to be readily exposed while the rest of the body remains covered, by partially opening any one of the fasteners.

I claim:

A garment adapted to cover the trunk and limbs of the body and including a hood for the head, the 20 hood and trunk portion of the garment having a

continuous longitudinal opening, the leg portions of the garment having openings branching from the longitudinal opening at the crotch of the garment and extending down the respective leg portions of the garment, and fastening means for the openings, each of said fastening means comprising cooperating rows of projections at the respective edges of an opening, and means 5 slideable in either of opposite directions along said cooperating rows of projections for successively interlocking the cooperating projections or successively disengaging the same, the sliding means for the longitudinal opening being adapted to slide downwardly along its opening for interlocking its cooperating rows of projections, and the 10 sliding means for each of the leg openings being adapted to slide upwardly along its opening for interlocking its cooperating rows of projections.
